UNITED STATES PATENT OFFICE.

CHARLES H. NITSCH AND WILLIAM A. WEIGHTMAN, OF LOGAN, PHILADELPHIA, PENNSYLVANIA, ASSIGNORS TO STOKES & SMITH COMPANY, OF SUMMERDALE, PHILADELPHIA, PENNSYLVANIA, A CORPORATION OF PENNSYLVANIA.

LABELING MACHINE.

Application filed March 1, 1922. Serial No. 540,288.

To all whom it may concern:

Be it known that we, CHARLES H. NITSCH and WILLIAM A. WEIGHTMAN, citizens of the United States, and residents of Logan, 5 Philadelphia, in the county of Philadelphia and State of Pennsylvania, have invented certain new and useful Improvements in Labeling Machines, of which the following is a specification.

10 The invention relates to machines for applying labels to articles and packages, and especially adapted for applying revenue stamps to cigarette packages.

Since certain peculiar problems are involved in stamping these packages according to one general method, and since the invention provides a satisfactory solution of these problems, it will be here described as physically embodied in a machine for that 20 particular purpose; but it will be evident after considering this embodiment that the invention is adaptable for other uses where some or all conditions are similar.

In order to avoid difficulties involved in cutting sheets of revenue stamps up into individual stamps, and supplying these from individual magazines for application to the packages, and certain disadvantages of labeling machines organized in accordance with that plan of stamp arrangement, it has been proposed to cut the stamp sheets into strips, each consisting of a plurality of stamps, place these strips in stacks in a magazine, feed the strips singly therefrom, 35 cut the strips to separate the individual stamps, apply adhesive, and then move the individual stamps onward toward applying position, while concurrently moving the stamps apart, to arrange them favorably for 40 application to a row of packages positioned to receive them.

A machine designed to operate on this plan is disclosed in the patent to Fogde and Southwick, No. 1,244,438, October 23, 1917, 45 and a machine of the same general type, with certain variations and improvements is described in the patent to the same inventors, No. 1,435,458, November 14, 1922; and the special problems involved in this class of 50 machines, so far as they are elucidated in the above disclosures, will not be described herein, except as may be necessary for an understanding of the present improvements.

The machines of the above mentioned 55 patents employ "pickers" or selecting devices, which by the application of "suction" lift a single stamp strip from a magazine containing a stack of strips, and retain the strip while it is cut, and thereafter the individual pickers or "suction heads" retain 60 the individual stamps by the same force of "suction" (or more properly by external atmospheric pressure in conjunction with lower pressure maintained in the heads) 65 while the stamps are cut, gummed, separated, and moved to application position.

While these machines represent great improvements over hand stamping and previous machines, and operate successfully in many respects, they fail to attain the greatest efficiency, for reasons connected chiefly with the pneumatic system of strip selecting and stamp-transport to applying position, and with the method of supplying strips 70 directly from the magazine to the carrying 75 heads.

In respect to the pneumatic selection and transport, it is found that this method of holding the stamps is not sufficiently positive; stamps frequently fail to adhere, or 80 are pulled from the suction heads by the glue roll when glue of desirable "strength," or adhesive quality, is used; in absence of stamps glue is frequently applied to the suction heads, with obvious resulting delay 85 and annoyance; this last difficulty is sought to be avoided, in the pending application, by devices for releasing the gluing element 90 from its operative connection in absence of a stamp from a suction head, but these devices, aside from their complication, do not avoid the annoyance of stamps falling from the suction heads; and in respect to the magazine and initial feed arrangement, 95 it is found that strips frequently adhere together and are removed two at a time by the suction heads; this often results in one strip being improperly cut and the stamps wasted, or else the stamps of the lower strip fall about the machine indiscriminately, 100 often getting mixed up with the glue or glue roll, and this double feeding also frequently prevents proper gluing of the upper stamps, and failure to stamp the packages. Other 105 objections and difficulties are well known to persons skilled in this art.

2

A principal object of the present invention is to avoid the difficulties connected with pneumatic selection and transport by providing positive gripping devices associated with the stamp carrying heads; to avoid difficulties connected with the magazine and initial feed arrangement by making the initial stamp-strip feed an independent function from the initial grasping of the strip by the carrier-heads; and to properly co-relate these features with each other and with other essential features of a stamping machine of this general type.

Another object is to reduce and practically entirely eliminate the possibility of applying glue to the stamp carriers, by suitable relative formation and arrangement of the carriers and glue applying instrumentality.

Another object is to provide for top replenishment of the strip magazine, and to otherwise improve the initial feed mechanism and its cooperation with other features of the machine.

Another object is to provide new and improved transfer mechanism for carrying the strips from the initial feed mechanism to the point of application to the carrying heads.

These and other objects, advantages, and characteristics of the invention are sufficiently further explained hereafter, in connection with a detail description of the accompanying drawings, which illustrate one exemplifying embodiment of the invention.

35 After considering this, it will be evident that many variations of structure may be made within the principles of the invention, also that certain features are of value apart from others, as well as in combination as shown; 40 and we contemplate the employment of any structures which are within the scope of the appended claims.

In the drawings:

Fig. 1 is a top plan of a cigarette package stamping machine, embodying the invention, with some parts broken away.

Figure 2 is mainly a substantially central, longitudinal, vertical section, some parts, however, being shown in elevation.

50 Fig. 3 is a transverse, vertical section at 3-3, Fig. 2.

Fig. 4 is a positional view of the strip magazine and initial feed mechanism.

Fig. 5 is a sectional detail, enlarged, of 55 the stamp carriers or "heads" and associated parts, at the rear, or strip gripping position.

Fig. 6 is a detail, in elevation, of the carrier heads and grippers in relation to the glue roll.

60 Fig. 7 is a vertical section, in a plane and on a scale corresponding to Fig. 5, of the carrier heads and associated parts at the front, or stamp applying position.

Fig. 8 is a perspective view of a cigarette package, with a stamp applied, in accord-

ance with the mode of operation of the present machine.

Fig. 9 is a substantially diagrammatic elevation of the stamp strip transfer mechanism, adjacent parts being indicated in a fragmentary or elementary way.

Fig. 10 is a sectional detail, explanatory of the strip transfer mechanism.

Fig. 11 is a top plan, with parts broken away, of the glue tank, rolls and scrapers.

The machine is built upon and about a suitable frame, sufficient parts of which are shown in the drawings, including a main plate or table 1, which is supported on suitable legs or standards (not shown), and elevated longitudinal side members 2 supported by uprights 3, 4, resting on the table.

A carriage 5 carries the label gripping and applying mechanism. This carriage is in the general form of a cross piece 6 having longitudinal side extension 7, fitting in guide channels 8, located on frame side members 2, and the carriage is reciprocated by suitable means, sufficiently indicated by a link

9 pivotally connected to the carriage at 10. At the forward or label applying end of the machine (at the left in Fig. 2) the table has an elevated portion 1^a, and a package feed belt 11 is arranged to move in a shallow groove in this table surface. The package belt is provided with upwardly projecting package feed members or pushing blades 12 arranged at regular intervals so as to accommodate between each of two

blades a row consisting of a suitable number of packages P, which are in the present instance cigarette packages of the well known pouch type, arranged five in each group, with the packages upright and with their narrower sides in contact. Evidently the number of packages in each row or group may be varied within any reasonable limits, and the label handling mechanism as hereinafter described, may be adapted to simultaneously apply labels to any reasonable number of packages at once. At and adjacent to labeling position the packages P are located between vertical guide plates

13. The carriage 5 carries a plurality of label carrying and applying instrumentalities 14, adapted to receive and hold a label strip consisting of a row of unseparated labels, and these instrumentalities are mounted for a depression movement and also for a laterally divergent or separating movement

100 and are controlled in this movement by a cam plate 15 supported on uprights 16 and 17, and provided with cam slots 18, forward portions of some of which are directed di-

vergently, as at 19-20, Fig. 1. Between the 105 rearward location of the carriage, that is its position as shown in Fig. 2, where the applying instrumentalities receive the label strip, and the forward position, that is the

location of the package row P, are located

110

label carrying and applying instrumentalities 14, adapted to receive and hold a label strip consisting of a row of unseparated labels, and these instrumentalities are mounted for a depression movement and also for a laterally divergent or separating movement

115 and are controlled in this movement by a cam plate 15 supported on uprights 16 and 17, and provided with cam slots 18, forward portions of some of which are directed di-

vergently, as at 19-20, Fig. 1. Between the 120 rearward location of the carriage, that is its position as shown in Fig. 2, where the applying instrumentalities receive the label strip, and the forward position, that is the

location of the package row P, are located

125 label carrying and applying instrumentalities 14, adapted to receive and hold a label strip consisting of a row of unseparated labels, and these instrumentalities are mounted for a depression movement and also for a laterally divergent or separating movement

130 and are controlled in this movement by a cam plate 15 supported on uprights 16 and 17, and provided with cam slots 18, forward portions of some of which are directed di-

a series of cutters 21 to cut and separate the label strip into individual labels, and a gluing instrumentality including a glue roll 22 to adhesively condition the under faces 5 of the labels.

The package feed belt 11 is moved intermittently, and is supplied with packages in proper arrangement at a point anterior to labeling position. In each rest of the conveyor 10 it locates a package row for labeling. The carriage 5 is moved in properly timed relation to the feed belt. At its rearward position a label strip is supplied to the label carrying instrumentalities; the carriage is 15 then moved forward, the label strip is cut, the labels are gummed, the carrying instrumentalities are separated by the action of the cam slots to position the individual labels in centered relation to the individual packages; the labels are brought over the packages, and the carrying instrumentalities are depressed while the packages are at rest; the labels are applied and released; the applying instrumentalities are retracted, and the 20 carriage returns to rearward position while the labeled packages are moved on for further operations, such as turning down the projecting label ends, and the operations are repeated indefinitely. As so far described, the machine and its mode of operation are substantially as in the previously mentioned patent and pending application to which reference should be made for an understanding of suitable or representative 25 forms of driving connections and other parts of the mechanism not particularly shown or described herein.

The carriage 5 is provided with parallel transverse round rods 25, Figs. 5 and 7, 40 supported by the carriage side members 7. Each label carrier 14 includes a block 26 mounted to slide on these rods, and a vertically movable head 27 guided by a pin 28 secured in an extension on block 26. A label 45 receiving plate 29 is supported below the head 27 by side pieces 30. A sleeve 31 is fixed in an aperture in the block 26 and has a portion 32 located in one of the cam slots 18 so that in the longitudinal movement of the carriage the entire applying unit is 50 directed properly and the outer ones are moved laterally as they approach the forward end of carriage travel by the angular portions 19 and 20 of the outward cam slots, 55 the central cam slot being straight, since in the present package arrangement the central applying instrumentality may be at all times in line with the central package. Each head 27 is fixedly connected to a 60 round bar 33 vertically movable within sleeve 31. Conveniently the lower end of this bar is screw-threaded and screwed tightly into the block. The upper portion of the bar 33 is bored out to form a tubular 65 portion 34, and on the upper end of this is

provided a shifting collar consisting specifically of disks 35 engaging exterior screw threads on the sleeve, and lock nuts 36, also engaging the screw threads, so that the disks may be adjusted and locked, not only to form an annular shifting groove 37 of proper vertical width, but to properly adjust the position of this groove vertically in relation to shifting and holding elements which cooperate with the shifting collar, as 70 presently described. The heads 27 are normally supported in their uppermost position, in contact with blocks 26, by springs 38 compressed between the lower nuts 36 and washers 39 resting on the upper ends of sleeves 31. The lower portion of the rod 33 is also bored out to form a tubular portion 40, in the lower end of which is mounted a vertically movable plunger 41 having a cleved end pivotally connected to a lever 42 fulcrumed on a pin 43 mounted in the side pieces 30. The outward end of this lever is provided with a pin 44 engaging a slot 45 in one arm of a gripper lever 46 mounted on a pin 47 located in forward extensions of the side plates 30. The gripper lever has a suitably curved or hook-shaped gripper 48 arranged to engage the forward margin of a label strip S and clamp the strip against the plate 29. The plunger 41 is connected to a rod 49 passing through a hole in a central portion of the bar 33 and this rod is operatively integral with a portion 50 of larger diameter slidably mounted in the sleeve 34. A spring 51 compressed between plunger 41 and a shoulder at the upper end of sleeve 40, normally urges the gripper 48 to gripping position. A shifting collar 52 having an annular shifting groove 53 has a 100 screw-threaded engagement with the upper end of rod 50 and is secured in adjusted position by a lock-nut 54.

At the rear carriage position, as shown in Fig. 5, the shifting grooves 37 of rods 33 cooperate with fingers 55 formed on a plate 56 110 fixedly supported by a bracket 57 resting on the cam plate, these fingers defining longitudinal slots 58 of substantial length to accommodate portions of sleeves 34 between the shifting disks 35, and the forward corners of the fingers being rounded or beveled as at 59 to facilitate the entry of these sleeve portions between the fingers. As the carriage nears its rearmost position the heads 27 are held in normal, elevated position by the springs 38, and the shifting collars are then brought into engagement with the holding fingers 55, the disks 35 overlying the margins of these fingers, and during the further slight rearward movement of the carriage, and while the carriage is stationary at label receiving position, by the described means, the heads 27 and the label receiving plates 29 are held positively in elevated position, to receive the label strip. 120

125

130

At the same time the shifting grooves 53 of rods 50 are brought into cooperation in a similar way with shifting fingers 60 formed on a plate 61, the fingers defining shifting 5 shots 62 and having rounded or beveled corners 63, substantially as and for the same purpose as similar parts of the head retaining structure just described. The plate 61 is secured to a vertically movable member 65 10 having rearwardly extending arms 66 secured to the upper ends of rods 67, suitably guided for vertical reciprocation in upright 16. The lower ends of these rods are connected to a cross piece 68 which has a cam 15 roller 69 engaging a cam groove 70 in a circular cam body 71 carried by a shaft 72. The cam groove is contoured so that as the carriage approaches rearmost position the plate 61 is elevated, and the shifting collars 20 52 are engaged with the shifting fingers 60, the cross bar 68 with its rods 67 is then moved down and plate 61 is depressed and the grippers are all simultaneously retracted, so that when the carriage comes to rest 25 in the position shown in Fig. 5 the grippers are in label receiving position.

Near the forward end of the frame, as best shown in Fig. 2, is an applier head operating plate 75 having fingers 76 defining 30 shifting slots 77 and corresponding substantially to the plate 56, previously described, the plate 75, however, being mounted for vertical reciprocation on a pair of sleeves 78, the lower ends of which are connected to 35 a cross piece 79 having a cam roller 80 engaging a cam groove in a cam body 81 on shaft 72. The cam groove acting on roller 80 is contoured so that as the carriage approaches forward position the plate 75 is 40 elevated and fingers 77 are engaged with the shifting collars of the label carriers and thereafter at about the time that the carriage is stationary in forward position the sleeve 78 and plate 75 are depressed and the 45 carrier heads 27, and connected parts are depressed and the individual labels carried by plates 29 are pressed upon the upper ends of the packages P in the position shown in Fig. 8, in which L is one of the individual 50 labels or revenue stamps. Approximately above plate 75 is a shifter plate 82 with shifting fingers 83, corresponding to the plate 61 previously described. Plate 82 is carried by rods 84 arranged to reciprocate 55 in the sleeves 78 and the lower ends of these rods are connected to a cross piece 85 provided with a cam roller 86 engaging the periphery of a cam 87 on shaft 72. The cam is contoured so that as the shifting collars 60 52 approach forward position they are properly engaged with the shifting fingers 83. The cam then causes the cam plate 82 to be depressed in unison with the plate 75, and then while the plate 75 is still depressed the 65 shifting plate 82 is raised, thus elevating all

of the rods 50 and opening the grippers to release the stamps. The plate 75 is then raised to restore the carrier heads to normal elevated position and at about this time, or as the carriage commences its rearward 70 movement, the plate 82 is lowered and the grippers resume their normal position at or about the time that the shifting collars 52 are freed from their forward operating plate. The shifting slots in plates 75 and 82 75 are, of course, spaced apart to agree with the separated positions of the carrier heads and the two sets of shifting collars, as clearly shown in Fig. 1.

In the patented machine, and also in that described in the above-mentioned application, the label carriers at label receiving position are depressed to receive a label-strip from a magazine containing a stack of strips; and various difficulties, including 80 sticking together of two or more strips, delay or annoyance in replenishing the magazine, and others understood by persons skilled in the art, result from this magazine location and method of "feeding" strips to the carriers. To avoid these difficulties, and to generally improve the construction and operation of the machine, in the present invention the label or stamp strips S are preferably arranged in a stack, in a container 85 or magazine 90, located considerably away from the label carriers, (Fig. 3) and labels are taken singly from the magazine and conveyed, in suitably timed relation, to the carrying heads. Specifically, in the present 90 embodiment the label strip feed and conveying mechanism comprises the following: The magazine 90 has a bottom plate 91, side plates or walls 92, and a rear wall 93, and is arranged to be reciprocated on inclined guides 94 by a lever 95, pivotally mounted at 96 on a frame member 97, and connected to the magazine by a link 98. The lever is oscillated by an eccentric strap and link 99, and eccentric 100 on a shaft 101, driven by gears 102 and 103 from a shaft 104, which is in turn driven from shaft 72 by sprockets and a chain 105. Thus the magazine is reciprocated in properly 105 timed relation, during each cycle of the machine. The base plate 91 is only long enough to support the rearward portion of the strip stack, the forward bottom portion 107 of the magazine being open. A suction roll 108 on a shaft 109 mounted in fixed bearings 110 engages the bottom strip, and by suction acting through the roll aperture 111 at about the moment the magazine starts 115 forward in the feeding action, the forward end of the strip adheres to the roll, which is rotated by a pinion 112 and rack 113 connected to move with the magazine. The suction mechanism and control may be as usual in feed apparatus of this class. The deflected strip end runs under a wedge or 120 125 130

guide 114 carried by an arm 115 secured to a fixed support 116; the "suction" is broken to free the strip from the suction roll, and shortly thereafter the strip is directed to engagement with a feed roll 117 cooperating with a feed or strip conveyor belt 118. During the rearward movement of the magazine the strip is withdrawn and fed onward by the feed roll and belt. When the bottom strip is deflected, the forward portion of the stack is supported by fingers 119 carried by arms 120 depending from a rock shaft 121 movably mounted in extensions 122 of side plates 92; and these fingers are retracted at the rearward stack position by a pin or screw 123 adjustably mounted in an arm 124 connected to shaft 121, and provided with a lock-nut 125, the end of this screw being arranged to engage a fixed stop in the form 20 of a pin 126.

The strip feed belt 118 runs on pulleys 130 and 131, and pulley 130 is driven by a gear 132 on its shaft 133, engaging gear 102 of shaft 101. Feed roll 117 is desirably 25 driven positively by a pinion 134 on its shaft 135 engaging a pinion on shaft 133. The upper stretch of the feed belt runs over a plate 136, and passes below the label receiving plates 29 in their rearward position, Fig. 30 5. The label strips are held with sufficient positiveness upon the belt surface by a guide wire 137 which lies close to the belt surface, and passes below the plates 29. One end of the wire is connected to an arm 138 depending from support 116, previously mentioned, and the other end is connected to an adjustable pin 139, screw-threaded and passing through a bracket-arm 140, and provided with nuts 141, so that the tension of the 40 guide-wire may be regulated. Rolls 142 cooperate with the guide wire and belt. These are of suitable number, so that the advancing strip may at all times be engaged by at least one of the rolls. The rolls are revolvably mounted on rods or arms 143 extending from any suitable frame member or fixed support 144, and have central channels 145 to accommodate the guide wire.

An advancing label strip is brought to 50 rest against a stop 146 at about the time the carriage 5 reaches its rear position; and the forward margin of the strip then lies above one, or usually a row of lifting pins 147, located in holes in plate 136, and actuated by 55 a bar 148, carried by arms 149 extending from a rock-shaft 150, mounted in brackets 151 and provided with an upright arm 152 in which a tappet 153 is adjustably screwed, and secured by a lock nut 154. The individual pins 147, or bar 148, may be retracted by one or more springs 156. The forward end of tappet 153 is engaged by a part of the carriage, so that as the carriage completes its rearward movement the rock-shaft is oscillated and pins 147 are lifted, bringing the

strip margin into close contact with forward portions of the carrying plates 29, and in proper position for engagement by grippers 48. The grippers then engage the strip, and it is carried forward for cutting and gluing. 70

The cutters 21 are in the form of sharp-edged circular blades, or disks, carried by a shaft 160, and this shaft is desirably driven at a high speed by independent driving means, such as the electric motor 161, mounted on base plate 1, and connected to shaft 160 by a belt 162 and pulleys. This provides a suitable high speed drive for the cutters without the complication of a train of speed multiplying gearing, although, of course, such a gear drive interconnected with some other part of the machine may be provided, instead of the independent motor. The cutter edges are in line with spaces 163 between the carrier heads 27. As the heads in their converged position, as shown in Fig. 6, carry the label strip past the cutters, the strip is divided into independent labels 1. Before the heads commence to move apart the labels are carried over and in contact with the glue roll 22, which is mounted on a shaft 165 supported in bearings 166 on the glue tank 167. The roll shaft 165 has a driving gear 210 engaging a gear 211 on a shaft 212 and gear 211 engages a gear 213 on a shaft 214, which also has a spiral gear 215, engaging a spiral gear 216 on shaft 72, for driving the glue roll. Below the glue roll is a dipper roll 168 which supplies glue to the glue roll. 85

The label carrying faces of the plates 29 are provided with narrow ribs 170 alternating with channels, and the roll surface is formed with a plurality of narrow ribs 172, alternating with channels, the ribs of plates 29 and the roll being interspaced, or in other words, arranged so that ribs on the one are opposite channels on the other, as sufficiently shown in Fig. 6. The glue roll is also provided with deeper and wider channels 174 to permit the grippers 46 to pass without conflict with the glue roll and without touching any glued surface. When a label is in proper position on any of the carrier plates 29 it is supported by the ribs 170 and its lower surface is brought properly in contact with the glue roll ribs 172 and narrow parallel stripes of glue are applied to the label surface. These are sufficient to cause the label or stamp to properly adhere to the package, and in fact, in the application of the stamps to the packages and subsequent pressing of the stamps in position on the packages, these glue stripes spread more or less and provide an ample adhesive engagement of the stamp with the package. If, however, for any reason a label is absent from the carrying plate 29 during advance movement of the carriage, there is no possibility of contact between ribs 170 and 172, 100

and, therefore, it is impossible for any glue to be applied to the carrier surface. Similarly, in return movement of the carriers it is not necessary to elevate them to avoid 5 the glue roll, or to depress the glue roll, or in fact, to make any special provision to avoid the contact of the carrier surface with any glued surfaces, since the carrier ribs always pass opposite channels of the glue 10 roll or substantially between the roll ribs. The carrier ribs 170 are located sufficiently close together so that the stamps are not appreciably bent by contact with the glue roll ribs; also the area of the glue stripes is so 15 small that there is no appreciable tendency to pull the labels away from the carrying faces or from the grippers.

It is desirable to provide means to regulate the amount of glue on the crests of ribs 172. 20 For this purpose a scraper plate 176 is adjustably mounted on a wall of the glue tank by means of slots 177 and screws 178, and this plate has an edge conformed substantially to the conformation of the roll surface; that is it has teeth 179 fitting closely 25 the sides of the roll ribs 172, and at the bases of these teeth the plate is slotted out slightly as at 180, providing narrow grooves of substantially rectangular outline, or in other 30 words, spaces which determine the amount of glue remaining on the crests of the ribs for application to the labels. Desirably the sides of the ribs 172 are slightly beveled and the sides of the scraper teeth are similarly 35 formed so that the scraper head fits closely against the sides of the ribs and removes practically all of the glue therefrom. Desirably strippers in the form of pins or blades 182 carried by a plate 183, are provided, fitting 40 between certain of the roll ribs 172, to prevent labels running into the glue trough if for any reason they are released at this point. The dipper roll 168 is carried by a shaft 185 which has bearings in eccentric 45 blocks 186, and these are adjustable by means of slotted sectors 187 and screws 188, so that by moving the blocks angularly the axis of shaft 185 may be moved toward and from the glue roll axis to adjust the contact 50 between the glue roll and the dipper roll. Desirably, also, a scraper 188' is provided to regulate the amount of glue carried by the dipper roll, and this is mounted adjustably on a wall of the glue tank by means of 55 screws 189 passing through slots 190 in the scraper.

After gluing, the labels are separated to bring them in properly centered relation to the packages, by the diverging movement of 60 the carrier heads, as sufficiently described above. As the carrier heads approach labeling position the advancing ends of the stamps encounter a stop blade or plate 192, mounted on guide plate 13, this stop plate

being provided with apertures 193 to accommodate the grippers. 95

Cigarette packages of the class described are frequently provided with an inner wrapping W, which is exposed at the upper open end of the outer or pouch wrapper X; 70 and this inner wrapper has end flaps Y which sometimes tend to spring up or project, and interfere more or less with the proper movement of the stamps to application position and this displacement of the flaps may even prevent the proper positioning and securing of the stamps. To insure 75 the proper positioning of these flaps, flap depressers or holders in the form of blades 195 are mounted on a rock shaft 196 and are normally retracted, as shown in Fig. 2, 80 by a spring 197 connected to a pin 198 on the shaft. The depresser blades are properly positioned and spaced apart to avoid conflict with the advancing stamps and carrier heads; that is to say, they are arranged opposite the spaces between the now divergently separated heads, and in this position the depresser blades lie over portions of the flaps Y to one side of the stamp location, as 85 sufficiently indicated in Fig. 8. The rock shaft 196 has an arm 200 carrying a cam roller 201 in the path of a cam plate 202 secured to one of the carriage side members 7, and this cam plate has a rounded forward 90 face 203. As the carriage approaches its forward position the cam surface 203 engages roller 201 and oscillates rock shaft 196, moving the blades 195 down upon the 95 package flaps and holding flaps down flat for the proper reception of the stamps. As soon as the carriage retreats spring 197 returns the presser blades 195 to elevated position, so that the packages may freely move 100 away and a new set of packages come into 105 position.

What I claim is:—

1. In a labeling machine, in which a label strip is associated with a plurality of label carriers, the strip severed to free the individual labels, and the labels are adhesively conditioned, separated by divergent movement of the carriers during their advance to labeling position and applied to a row of packages at labeling position, positive label gripping means associated with the label carriers, and means for advancing a label strip consisting of a series of connected labels and positioning the strip below the label carriers ready for grasping by the gripping means. 110

2. In a labeling machine, in which a label strip is associated with a plurality of label carriers, the strip severed to free the individual labels, and the labels are adhesively conditioned, separated by divergent movement of the carriers during their advance to labeling position, and applied to a row of 115 120 125

- packages at labeling position, the combination with the label carriers of positive label gripping means, and means for advancing a label strip consisting of a series of connected labels and positioning the strip below the label carriers ready for grasping by the gripping means. 65
3. In a labeling machine, in which a label strip is associated with a plurality of label carriers, the strip severed to free the individual labels, and the labels are adhesively conditioned, separated by divergent movement of the carriers during their advance to labeling position and applied to a row of packages at labeling position, the combination with the carriers of positive label grippers, means for operating the grippers to grasp and securely hold the label strip at a label receiving position, to positively retain the individual labels after severing and while being adhesively conditioned and to release the labels at applying position, and means for advancing a label strip consisting of a series of connected labels and 70 positioning the strip below the label carriers ready for grasping by the grippers. 75
4. In a labeling machine, in which a label strip is associated with a plurality of label carriers, the strip severed to free the individual labels, and the labels are adhesively conditioned, separated by divergent movement of the carriers during their advance to labeling position and applied to a row of packages at labeling position, the combination with the carriers of positive label grippers, means for operating the grippers to grasp and securely hold the label strip at a label receiving position, to positively retain the individual labels after severing 80 and while being adhesively conditioned and to release the labels at applying position, means for advancing label strips to label receiving position, and means for lifting the strip to aid the gripping action. 85
5. In a labeling machine, in which a label strip is associated with a plurality of label carriers, the strip severed to free the individual labels, and the labels are adhesively conditioned, separated by divergent movement of the carriers during their advance to labeling position and applied to a row of packages at labeling position, a holder for a stack of label strips, means for feeding individual strips successively from the holder, means for advancing the strips to strip receiving position of the carriers in timed relation to the carrier movements, and means for positioning the label strip in relation to the carriers at the label receiving 90 position. 95
6. In a labeling machine, in which a label strip is associated with a plurality of label carriers, the strip severed to free the individual labels, and the labels are adhesively 100
- conditioned, separated by divergent movement of the carriers during their advance to labeling position and applied to a row of packages at labeling position, positive label gripping means associated with the label carriers, a holder for a stack of label strips, means for feeding individual strips successively from the holder, means for advancing the strips to strip receiving position of the carriers in timed relation to the carrier movements, and means for locating the strip at label receiving position with each individual label in the strip arranged for gripping by one of the individual carrier grippers. 105
7. In a labeling machine, in which a label strip is associated with a plurality of label carriers, the strip severed to free the individual labels, and the labels are adhesively conditioned, separated by divergent movement of the carriers during their advance to labeling position and applied to a row of packages at labeling position, a carriage, means for moving it to and fro, a plurality of label carriers mounted for lateral movement on the carriage and also mounted for a depression movement, a label gripper on each carrier, means for depressing the carriers at one end of the carriage travel, and means for operating the grippers at one end of the carriage travel to engage labels and at the other end of the travel to release them. 110
8. In a labeling machine, in which a label strip is associated with a plurality of label carriers, the strip severed to free the individual labels, and the labels are adhesively conditioned, separated by divergent movement of the carriers during their advance to labeling position and applied to a row of packages at labeling position, a carriage, means for moving it to and fro, a plurality of label carriers mounted for lateral movement on the carriage and also mounted for a depression movement, a positive label gripper on each carrier, means for depressing the carriers at the delivery end of the carriage travel, and means for operating the grippers at the receiving end of the carriage travel to engage labels at the other end of the travel to release them. 115
9. Labeling mechanism comprising a carriage having to and fro movement, a plurality of label carriers mounted thereon for lateral divergent movement and for a depression movement, a positive label gripper for each carrier, means controlling lateral movement of the carriers, means engaged with the carriers at label delivery position for depressing and returning them, and means engaged with the grippers at each end of the carriage movement for operating the grippers. 120
10. Labeling mechanism comprising a carriage having to and fro movement, a plurality of label carriers mounted thereon for 125

lateral divergent movement and for a depression movement, a positive label gripper on each carrier, means controlling lateral movement of the carriers, means engaged with the carriers at label delivery position for depressing and returning them, means engaged with the grippers at each end of the carriage movement for operating the grippers, and a glue roll, the roll and adjacent carrier surfaces being provided with interspaced ribs to insure glue application to labels and prevent glue application to the carrier surfaces.

11. Labeling mechanism comprising a carriage having to and fro movement, a plurality of label carriers mounted thereon for lateral divergent movement and for a depression movement, a positive label gripper for each carrier, means controlling lateral movement of the carriers, means engaged with the carriers at label delivery position for depressing and returning them, means engaged with the carriers at label receiving position to prevent depression movement, and means engaged with the grippers at each end of the carriage movement for operating the grippers.

12. Labeling mechanism comprising a carriage having to and fro movement, a plurality of label carriers mounted thereon for lateral divergent movement and for a depression movement, a positive label gripper on each carrier, means controlling lateral movement of the carriers, means engaged with the carriers at label delivery position for depressing and returning them, means engaged with the carriers at label receiving position to prevent depression movement, means engaged with the grippers at each end of the carriage movement for operating the grippers, and a glue roll, the roll and adjacent carrier surfaces being provided with interspaced ribs to insure glue application to labels and prevent glue application to the carrier surfaces.

13. Labeling mechanism comprising a reciprocating carriage, a plurality of label carriers mounted thereon for divergent movement and for vertical movement, means for moving the carriers divergently and for returning them during movements of the carriage, vertical shifting collars connected to the carriers, a series of shifters engaged with the collars at delivery position of the carriage, means for moving the shifters to depress the carriers, positive label grippers on the carriers, gripper operating means including shifting collars, a series of shifters engaging the gripper shifting collars at each end of the carriage movement, and means for operating the last named series of shifters.

14. Labeling mechanism comprising a reciprocating carriage, a plurality of label carriers mounted thereon for lateral divergent movement and for vertical movement, means for moving the carriers divergently

and for returning them convergently during to and fro movements of the carriage, label slitters and a glue roll arranged for label contact while the carriers are convergently located in their advance movements, vertical shifting collars connected to the carriers, a series of shifters engaged with the collars at delivery position of the carriage, means for moving the shifters to depress the carriers, positive label grippers on the carriers, gripper operating means including shifting collars, a series of shifters engaging the gripper shifting collars at each end of the carriage movement, and means for operating the last named series of shifters.

15. Labeling mechanism comprising a reciprocating carriage, a plurality of label carriers mounted thereon for divergent movement and for vertical movement, means for moving the carriers divergently and for returning them during movements of the carriage, vertical shifting collars connected to the carriers, a series of shifters engaged with the collars at delivery position of the carriage, means for moving the shifters to depress the carriers, a series of retaining members engaging the carrier collars at label receiving position to prevent depression movement, positive label grippers on the carriers, gripper operating means including shifting collars, a series of shifters engaging the gripper shifting collars at each end of the carriage movement, and means for operating the last named series of shifters.

16. Labeling mechanism comprising a reciprocating carriage, a plurality of label carriers mounted thereon for lateral divergent movement and for vertical movement, means for moving the carriers divergently and for returning them convergently during to and fro movements of the carriage, label slitters and a glue roll arranged for label contact while the carriers are convergently located in their advance movements, vertical shifting collars connected to the carriers, a series of shifters engaged with the collars at delivery position of the carriage, means for moving the shifters to depress the carriers, a series of retaining members engaging the carrier collars at label receiving position to prevent depression movement, positive label grippers on the carriers, gripper operating means including shifting collars, a series of shifters engaging the gripper shifting collars at each end of the carriage movement, and means for operating the last named series of shifters.

17. In labeling mechanism of the class described, means for positioning articles to be labeled, means for supplying labels, a label carrier, means for securing a label to the carrier, a glue applier, and means for moving the carrier past the glue applier, adjacent faces of the carrier and the ap-

plier being mutually conformed to prevent application of glue to the carrier in the absence of a label.

18. In labeling mechanism of the class described, means for positioning articles to be labeled, means for supplying labels, a label carrier, a gripper for securing a label to the carrier, a glue applier, and means for moving the carrier past the glue applier, adjacent faces of the carrier and the applier being mutually conformed to glue the label and prevent application of glue to the carrier in absence of a label.

19. In labeling mechanism of the class described, means for positioning articles to be labeled, means for supplying labels, a label carrier, means for securing a label to the carrier, a glue applier, and means for moving the carrier past the glue applier, the active faces of the carrier and the glue applier being provided with interspaced ribs with substantial clearance so that a label properly positioned on the carrier receives stripes of glue from the gluer ribs, and in the absence of a label the carrier surface does not come in contact with glue.

20. In labeling mechanism of the class described, means for positioning articles to be labeled, means for supplying labels, a label carrier, means for securing a label to the carrier, a glue applier, and means for moving the carrier past the glue applier, the active faces of the carrier and the glue applier being provided with narrow, interfitting ribs and rib spaces with substantial clearance, so that a label properly positioned on the carrier receives stripes of glue from the gluer ribs, and in the absence of a label the carrier surface does not come in contact with glue.

21. In a labeling machine, means for positioning articles to be labeled, means for supplying labels, a glue roll, glue supply means, a label carrier, the glue roll and the carrier being provided with ribs and channels, the ribs on one being arranged in opposition to the channels on the other, whereby when a stamp is positioned on the carrier it receives glue stripes from the glue roll and in the absence of a label, contact of the carrier face with the glue carrying surfaces of the roll is prevented.

22. In a labeling machine, means for positioning articles to be labeled, means for supplying labels, a glue roll, glue supply means, a label carrier having to and fro movement, means for securing a label to the carrier the glue roll and the carrier being provided with interspaced ribs and channels, whereby when a stamp is positioned on the carrier it receives glue stripes from the glue roll ribs and in the absence of a label, contact of the carrier face with the glue carrying surfaces of the roll is prevented.

23. In a labeling machine, means for posi-

tioning articles to be labeled, means for supplying labels, a glue roll, means for supplying glue to the roll, a label carrier having to and fro movement, a label gripper on the carrier, the glue roll and the carrier being provided with narrow ribs and channels, the ribs on one being arranged in opposition to the channels on the other, whereby when a stamp is positioned on the carrier it receives narrow glue stripes from the glue roll ribs and in the absence of a label, contact of the carrier face with the glue carrying surfaces of the roll is prevented, the glue roll being provided with a channel to accommodate the label gripper.

24. In a labeling machine, means for positioning articles to be labeled, means for supplying labels, a glue roll, means for supplying glue to the roll, a label carrier having to and fro movement, a positive label gripper on the carrier, the glue roll and the carrier being provided with relatively narrow ribs and channels, the ribs on one being arranged in opposition to the channels on the other and the rib crests being positioned to pass each other in nearly the same plane, whereby when a stamp is positioned on the carrier it receives narrow glue stripes from the glue roll ribs, and in the absence of a label contact of the carrier face with the glue carrying surfaces of the roll is prevented, the glue roll being provided with a channel to accommodate the label gripper.

25. In a labeling machine, means for positioning articles to be labeled, means for supplying labels, a glue roll, means for supplying glue to the roll, a plurality of label carriers having to and fro movement, a positive label gripper on each carrier, the glue roll and the carriers being provided with ribs and channels, the ribs on one being arranged in opposition to the channels on the others, and the rib crests being positioned to pass each other in nearly the same plane, whereby when labels are positioned on the carriers they receive narrow glue stripes from the glue roll ribs and in the absence of a label contact of the carrier face with the glue carrying surface of the roll is prevented.

26. In a labeling machine, means for positioning articles to be labeled, means for supplying labels, a glue roll, means for supplying glue to the roll, a plurality of independent label carriers having to and fro movement, a positive label gripper on each carrier, the glue roll and the carriers being provided with relatively narrow ribs and channels, the ribs on the roll being arranged in opposition to the channels of the carriers and the rib crests being positioned to pass each other in nearly the same plane, whereby when labels are positioned on the carriers they receive narrow glue stripes.

- from the glue roll ribs, and in the absence of a label contact of the carrier face with the glue carrying surface of the roll is prevented, the glue roll being provided with 5 channels to accommodate the label grippers.
27. A labeling machine comprising, means for positioning packages for labeling, a carriage having to and fro movement, a label carrier thereon, a label gripper on the carrier, means for operating the gripper, means for advancing a label into opposed relation to the carrier surface, and means for elevating an edge of the label.
28. A labeling machine comprising, means 15 for positioning packages for labeling, a carriage having to and fro movement, a label carrier thereon, a label gripper on the carrier, means for operating the gripper, means for advancing a label into opposed relation 20 to the carrier surface, and means operated by carriage movement for moving an edge of the label into close contact with the carrier surface prior to gripper engagement.
29. A labeling machine comprising, means 25 for positioning packages for labeling, a carriage having to and fro movement, a label carrier thereon, a label gripper on the carrier, means for operating the gripper, means for advancing a label into opposed relation 30 to the carrier surface, a lifter pin over which the label is positioned, and means actuated by carriage movement for raising the pin to lift the label prior to closing movement of the gripper.
35. 30. A labeling machine comprising, means for positioning packages for labeling, a carriage having to and fro movement, a plurality of label carriers thereon, a label gripper on each carrier, means for operating 40 the grippers, means for advancing a label strip into opposed relation to the carrier surfaces, and means for elevating an edge of the label strip to insure proper engagement of the grippers.
45. 31. A labeling machine comprising, means for positioning packages for labeling, a carriage having to and fro movement, a plurality of label carriers thereon, a label gripper on each carrier, means for operating 50 the grippers, means for advancing a label strip into opposed relation to the carrier surfaces, and means operated by carriage movement for moving an edge of the label strip into close contact with the 55 carrier surfaces prior to gripper engagement.
32. A labeling machine comprising, means for positioning packages for labeling, a carriage having to and fro movement, a plurality of label carriers thereon, a label gripper on each carrier, means for operating 60 the grippers, means for advancing a label strip into opposed relation to the carrier surfaces, lifter pins over which the label 65 strip is positioned, and means actuated by

carriage movement for raising the pins to lift the label strip prior to closing movement of the grippers.

33. A labeling machine comprising a label carrier, means for supplying and securing a label thereto, means for moving the carrier to a label applying station, means for positioning a package at that station, and a presser acting on the label receiving end of the package and arranged 75 to avoid interference with the carrier and label.

34. A labeling machine comprising a label carrier, means for supplying and securing a label thereto, means for moving 80 the carrier to a label applying station, means for positioning a package at that station, a presser blade to depress package flaps, and means for operating the blade 85 to act on the package prior to label application.

35. A labeling machine comprising a plurality of label carriers, means for supplying and securing labels thereto, means for moving the carriers to a label applying station, means for positioning a row of packages 90 at that station, and pressers arranged to act on the label receiving ends of the packages and arranged to avoid interference with the carriers and labels.

36. A labeling machine comprising a plurality of label carriers, means for supplying and securing labels thereto, means for moving the carriers to a label applying station, means for positioning a row of packages 100 at that station, presser blades arranged to depress package flaps, and means for operating the blades to act on the packages prior to label application.

37. Labeling mechanism comprising a label carrier, label securing means on the carrier, means for feeding labels successively toward the carrier at label receiving position, and means for locating the labels on the feeding means during movement toward the stated position.

38. Labeling mechanism comprising a carriage, a plurality of label carriers thereon, label securing means on the carriers, means for feeding label strips successively 115 toward the carriers at label receiving position, and means for definitely locating the label strips on the feeding means during movement toward the stated position.

39. A labeling machine comprising a carriage, a plurality of label carriers thereon, a positive gripper for each carrier, a magazine for a stack of label strips, means for feeding individual strips successively from the magazine, a belt for carrying the label strips 125 to a position below the carriers, and a guide above the belt and advancing strips and below the carriers to retain the label strips on the belt during advance.

40. A labeling machine comprising a car- 130

- riage, a plurality of label carriers thereon, a positive gripper for each carrier, a magazine for a stack of label strips, means for feeding individual strips successively from the magazine, a belt for carrying the label strips to a position below the carriers, and a guide wire lying close above the belt surface and passing below the carrier faces to locate advancing labels on the belt.
41. A labeling machine comprising a carriage, a plurality of label carriers thereon, a positive gripper for each carrier, a magazine for a stack of label strips, means for feeding individual strips successively from the magazine, a belt for carrying the label strips to a position below the carriers, a guide located above the belt and advancing strips and below the carriers to retain the label strips on the belt during advance, and guide rolls associated with the guide and belt.
42. A labeling machine comprising a carriage, a plurality of label carriers thereon, a positive gripper for each carrier, a magazine for a stack of label strips, means for feeding individual strips successively from the magazine, a belt for carrying the label strips to a position below the carriers, a guide wire lying close above the belt surface and passing below the carrier faces to locate advancing labels on the belt, and guide rolls engaging the belt and label strips and channeled to accommodate the guide wire.
43. A labeling machine comprising means for positioning a row of packages to be labeled, means for advancing strips to a label receiving position, a reciprocating carriage, means for moving it from label receiving to label position and back, a plurality of label carriers on the carriage, means for depressing and raising the carriers at labeling position, means for moving the carriers divergently prior to the location of the carriage at labeling position, and for moving them convergently prior to location of the carriage at label receiving position, a positive label gripper on each carrier, means for opening and closing the grippers at each stated position, slitters to separate individual labels, and means for applying glue to the labels during advance of the carriage toward labeling position.
44. A labeling machine comprising means for positioning a row of packages to be labeled, means for advancing label strips to a label receiving position, a reciprocating carriage, means for moving it from label receiving to label applying position and back, a plurality of label carriers on the carriage, means for depressing and raising the carriers at labeling position, means for moving the carriers divergently prior to the location of the carriage at labeling position, and for moving them convergently to location of the carriage at label receiving position, a positive label gripper on each carrier, means for opening and closing the grippers at each stated position, slitters to separate individual labels, and means for applying glue to the labels during advance of the carriage toward labeling position.
45. A labeling machine comprising means for positioning a row of packages to be labeled, means for advancing strips to a label receiving position, a reciprocating carriage, means for moving it from label receiving to label position and back, a plurality of label carriers on the carriage, means for depressing and raising the carriers at labeling position, means for moving the carriers divergently prior to the location of the carriage at labeling position and for moving them convergently prior to location of the carriage at label receiving position, a positive label gripper on each carrier, means for opening and closing the grippers at each stated position, slitters to separate individual labels, and means for applying glue to the labels during advance of the carriage toward labeling position, package top depressers at labeling position, and means for operating the depressers prior to depression of the carriers at labeling position.
46. A labeling machine comprising means for positioning a row of packages to be labeled, means for advancing label strips to a label receiving position, a reciprocating carriage, means for moving it from label receiving to label applying position and back, a plurality of label carriers on the carriage, means for depressing and raising the carriers at labeling position, means for moving the carriers divergently prior to the location of the carriage at labeling position, and for moving them convergently prior to location of the carriage at label receiving position, a positive label gripper on each carrier, means for opening and closing the grippers at each stated position, means operated by carriage movement for elevating an edge of the label strip at label receiving position, slitters to separate individual labels, means for applying glue to the labels during advance of the carriage toward labeling position, package stop depressers at labeling position, and means for operating the depressers prior to depression of the carriers at labeling position.
47. In a labeling machine of the class described, in combination with means for positioning articles to be labeled, and label supply means, a glue roll having a ribbed surface and a label carrier arranged for to and fro movement to carry labels past and over the glue roll, the carrier having a surface provided with ribs intermediate the ribs on the roll surface.
48. In a labeling machine, in combination

with means for positioning rows of articles to be labeled and label supply means, a glue roll having its surface provided with a multiplicity of annular gluing ribs, a plurality of label carriers having substantially flat label receiving faces, each face being provided with a plurality of ribs arranged to correspond with a plurality of the rib spaces of the glue roll, and means for moving the carriers to and fro between label receiving and label applying positions to carry labels in contact with the gluing ribs, the described construction being such that labels properly positioned on the carriers are glued as they pass over the annular gluing ribs, and in the absence of a label, the ribs on the carrier faces pass between the annular gluing ribs without receiving glue therefrom.

49. In a labeling machine, in combination with means for positioning rows of articles to be labeled and label supply means, a glue roll having its surface provided with a multiplicity of annular gluing ribs, a plurality of label carriers having substantially flat label receiving faces, each face being provided with a plurality of ribs arranged to correspond with a plurality of the rib spaces of the glue roll, and means for moving the carriers to and fro between label receiving and label applying positions to carry labels in contact with the gluing ribs, each of the carriers being provided with a positive label gripper and the glue roll being provided with annular channels to accommodate the grippers, the described construction being such that labels properly positioned on the carriers are glued as they pass over the annular gluing ribs, and in the absence of a label, the ribs on the carrier faces pass between the annular gluing ribs without receiving glue therefrom.

50. A labeling machine comprising means

for positioning packages to be labeled, label carriers having a to and fro movement and label supply mechanism comprising means for feeding individual label strips from a stack, a conveyor belt on which the strips are placed by the feed means, and rolls engaging the belt and label strips advancing thereon to retain the strips in properly spaced relation on the belt.

51. A labeling machine comprising means for positioning packages to be labeled, label carriers having a to and fro movement and label supply mechanism comprising means for feeding individual label strips from a stack, a conveyor belt on which the strips are placed by the feed means, rolls engaging the belt and label strips advancing thereon to retain the strips in properly spaced relation on the belt, and a stop to locate the label strips at label receiving position.

52. A labeling machine comprising means for positioning packages to be labeled, label carriers having a to and fro movement and label supply mechanism comprising means for feeding individual label strips from a stack, a conveyor belt on which the strips are placed by the feed means, rolls engaging the belt and label strips advancing thereon to retain the strips in properly spaced relation on the belt, a stop to locate the label strips at label receiving position, positive label grippers on the carriers, and means at label receiving position for raising an edge with a label strip in proximity to the carrier surface and ready to be assisted by the grippers.

Signed at Philadelphia, in the county of Philadelphia and State of Penna., this 25th day Feb., A. D. 1922.

CHARLES H. NITSCH.
WILLIAM A. WEIGHTMAN.
